(57) **CLAIM**

We claim the ornamental design for a case for electronic device, as shown and described.

DESCRIPTION

FIG. 1 is a front perspective view of a case for electronic device showing our new design;

FIG. 2 is a front view thereof;

FIG. 3 is a rear view thereof;

FIG. 4 is an enlarged left-side view thereof;

FIG. 5 is an enlarged right-side view thereof;

FIG. 6 is a top view thereof;

FIG. 7 bottom view thereof;

FIG. 8 is another front view, in which the case for electronic device is provided in an open position;

FIG. 9 is an enlarged rear view of FIG. 8;

FIG. 10 is another enlarged right-side view of FIG. 5, in which a mobile terminal in dot-dash broken lines is provided to illustrate an example environment;

FIG. 11 is another enlarged right-side view thereof, in which the case for electronic device is provided in an alternate position;

FIG. 12 is another enlarged right-side view thereof; in which the case for electronic device is provided in another alternate position; and,

FIG. 13 is another enlarged right-side view thereof; in which the case for electronic device is provided in another alternate position.

The broken lines along the perimeter represent stitching and form part of the claim. The broken lines shown on the feet in FIG. 9 are included for illustrative purposes only and form no part of the claim. The dot-dash broken lines shown on FIGS. 8 and 9 are included for illustrative purposes only and form no part of the claim. The dot-dash lines in FIGS. 10-13 represent a mobile terminal and form no part of the claim.
